Primary Examiner — Jack Reickel*Assistant Examiner* — Salamah Jordan(74) *Attorney, Agent, or Firm* — Browdy and Neimark, PLLC(57) **CLAIM**

The ornamental design for a seesaw, as shown and described.

DESCRIPTION

FIG. 1 is a perspective view of a seesaw, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front elevation view thereof showing the seesaw in use;

FIG. 9 is a front elevation view thereof showing the seesaw used as a core muscles balancing board; and,

FIG. 10 is a front elevation view thereof showing the seesaw in use and used as a core muscles balancing board at the same time.

The broken lines depict portions of the article and environment that form no part of the claimed design.

1 Claim, 10 Drawing Sheets(56)
